FOOT-OPERATED RATCHETING LEVER FOR
ACTUATING A TRAVELING NUT OF A
SCREW-OPERATED VISE

Ben E. Thomas, Coulee Dam, Wash.

Application January 2, 1948, Serial No. 189

2 Claims. (Cl. 81—17)

1

This invention relates to new and useful improvements in vises and the primary object of the present invention is to provide a bench vise including novel and improved foot operating means for actuating the movable jaw of said bench vise.

Another important object of the present invention is to provide a foot operated bench vise including a foot pedal operatively connected to the movable jaw of said vise and embodying novel and improved means for automatically locking said movable jaw in a step-by-step position relative to the fixed jaw of said vise each time the foot pedal is depressed.

Another object of the present invention is to provide a foot-operated vise including a foot pedal and means connecting said foot pedal to the movable jaw of a vise for normally retaining a constant pressure on the movable jaw during actuation of the foot pedal.

A further object of the present invention is to provide a foot-operated bench vise including a novel and improved foot-operating mechanism that is quickly and readily applied to or removed from the vise in a convenient manner.

A still further aim of the present invention is to provide a foot-operated vise that is simple and practical in construction, small and compact in structure, strong and reliable in use, neat and attractive in appearance, relatively inexpensive to manufacture, and otherwise well adapted for the purposes for which intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary perspective view of a bench and showing the foot-operated vise applied thereto;

Figure 2 is a front elevational view of the lower portion of the foot-operated vise and is taken on the line 2—2 of Figure 6;

Figure 3 is a top plan view taken substantially in the direction of arrow numbered 3 in Figure 2, but omitting the connecting chain;

Figure 4 is a side elevational view taken substantially in the direction of arrows 4 in Figure 2, but omitting certain parts;

2

Figure 5 is an enlarged longitudinal central section in elevation of the upper end of the foot-operated vise;

Figure 6 is an enlarged side elevational view of the lower portion of the foot-operated vise, with parts of the support standard and connecting chain broken away;

Figure 7 is an elevational view of the spring mounting incorporated in the connecting chain; and,

Figure 8 is fragmentary side elevational view of a modified spring connecting means used in the connecting chain.

Referring now to the drawings in detail, where-in for the purpose of illustration, there is disclosed a preferred embodiment of the present invention, the numeral 10 represents a bench vise generally, comprising a base 12, a fixed jaw 14 integrally formed with the base, a channeled shank 16 slidably mounted in a longitudinally channeled guide groove 18 provided in the base 12, a movable jaw 20 integrally formed with the shank 16, and a feed screw 22 rotatably mounted in an opening 24 provided in the lower end 26 of the movable jaw 20. An actuating handle 28 is fixed on the feed screw 22 for rotating the latter.

Removably secured by fasteners or the like 30 to the supporting wall 32 of a useful work bench 34, is a base 36 which is provided with a central opening 38 that aligns with a vertical opening 40 provided in the base 12. These openings 38 and 40 usually receive a pivot bolt whereby the base 12 may be rotatably adjusted relative to the base 36, however, in conjunction with the present invention, the bolt is replaced by an externally threaded guide sleeve 42 which is receivably engaged in the opening 40 and which threadingly engages a nut 44 that is positioned in a notch 46 provided in the supporting wall 32, and which frictionally engages the lower face of the base 36 for retaining the vise in a fixed position.

Suitably fixed to the lower face of the supporting wall 32, is the upper end of a support standard or frame 48 having a bearing pedestal or footing 50 at its lower end that frictionally engages a floor surface or the like 52.

Rotatably supported in a substantially transverse aperture 54 provided in the standard 48, is a bolt or shaft 56 having externally threaded ends 58 and 60.

Fixed for rotation with the shaft 56, preferably keyed to said shaft on opposite sides of the standard 48, is a sprocket 62 and a ratchet 64 that are prevented from longitudinal movement on the shaft 56 by lock nuts 66 threaded on the ends 58 and 60 of said shaft. Rigidly secured to the standard 48 and extending forwardly therefrom, is a support plate 68 having an internally threaded aperture 70 that mounts a bolt 72 which pivotally supports an angulated lever 74. One end of this lever 74 pivotally supports a pawl 76 for removable engagement with the ratchet 64. A bolt 78 (see Figure 6) loosely extends through the standard 48 at an inclined angle relative to the longitudinal axis of said standard 48, and is connected adjacent pawl 76 to the lever 74. A coil spring 80 mounted on the bolt 78 is biased between the standard 48 and a head 82 of said bolt for normally retaining the pawl 76 lockably engaged with the ratchet 64, as shown best in Figure 6 of the drawings.

Removably fixed on the shaft 56, adjacent the end 58 thereof and the ratchet 64, is one rounded corner 83 of a substantially triangular holding plate 84, one rounded corner 85 of which frictionally bears upon the bearing footing 58 and the remaining corner 86 of which is pivoted to an actuating lever or arm 90, adjacent the rear end 92 of said lever 90.

Rigidly secured to and laterally extending from the lever 90 is an attaching ear 94 that receives a depending bolt 96, which is threaded at its lower end into an internally threaded bore 98 carried by the corner 83 of the plate 84. A coil spring 100 mounted on the bolt 96 is biased between the ear 94 and bore 98, to normally retain the lever 90 in a substantially horizontal position. The rear end 92 of the lever 90 is connected to a further coil spring 102 that is imbedded or anchored to the floor 92 for also aiding in retaining the lever 90 in a substantially horizontal position. A foot pedal or pad 104 is fixed to the forward end 106 of the lever 90 at a convenient distance from the bench 34.

Mounted in the channeled groove 18 and within the shank 16, is a guide strip 108 that slidably supports a traveling nut block 110 that is threaded on the feed screw 22. A length of link chain 112 is fixed at one end 114 to the traveling block 110 and extends downwardly through the sleeve 42. The opposite end 116 of this chain 112 is pivoted to the outer portion 118 of a depending bolt 120 that slidably supports a pair of plates 122 and 124. Also slidably supporting the plates 122 and 124, is a further bolt 126 which is spaced parallel to the bolt 120 and which is provided with an eye portion 128 that is pivoted to the upper end 130 of a further length of link chain 132, the lower end 134 of which is fixed to the sprocket 62. A coil spring 136 loosely embraces the bolts 120 and 126 and is biased between the plates 122 and 124.

A pawl 138 integrally formed on the lever 90, is normally held out of engagement with the ratchet 64 by the springs 100 and 102.

Embracing a reduced inner end 140 of the feed screw 22, is a coil spring 142 that frictionally engages a closure plate 144 at one end of the channel groove 18 for urging the feed screw to an outward position to thereby open the jaw 20.

In practical use of the device, when the foot pedal 104 is depressed, the pawl 138 on the lever 90 rotates the ratchet wheel 64 which in turn revolves the sprocket wheel 62, pulling link chains 112 and 132 downwardly, thus pulling block 110

75 toward the closure plate 14 to effect a clamping action of the jaws 14 and 20. Ratchet dog 76 locks ratchet wheel 64 in a selected adjusted position of the jaw 20. When pressure is removed from pedal 104, spring 102 pulls lever 90 back to its normal horizontal position, and the lower corner 86 of the holding plate 84 engages the floor, thus preventing lever 90 from being raised above its normal position. Foot pedal 104 is depressed a sufficient number of times to close the jaws of the vise. The compression of spring 136 compensates for the spacing of the teeth on the ratchet wheel 64 and maintains a constant pressure on the movable jaw 20. Upon pushing the upper portion of the lever 74 toward the standard 48, the ratchet dog 76 is jack-knifed and disengages the ratchet wheel 64. When the ratchet wheel 64 is thus released, spring 142 expands and opens the vise.

When the vise is closed and locked into place, it may still be opened by the regular or normal handle 28. This handle 28 may also be used for setting the vise for a definite opening in those instances when the same size material will be successively clamped, and thus it will be only necessary to depress the foot pedal 104 once for a slight clamping engagement of the vice on the material to be worked upon.

Reference is now directed to Figure 8, wherein there is disclosed the spring connecting means for the ends 116 and 130 for the link chains 112 and 132 in slightly modified form. In this embodiment an open cage 146 depends from the end 116 of the link chain 112. This cage 146 is provided with a suitable aperture in its lower plate 148 that slidably supports a bolt or the like 150 that is pivotally connected to the link 130 of the chain 132. A suitable leaf type spring 152 loosely positioned on the bolt 150 is biased between the head portion 154 of the bolt and the lower plate 148 of the cage 146 to resiliently support the bolt 150 and to maintain the tautness of the chains 116 and 130 as the foot pedal 104 is being operated.

45 In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same 55 is susceptible to certain changes fully comprehended by the scope of the appended claims.

Having described my invention, what is claimed as new is:

1. A foot operated vise comprising a vise body 60 including a fixed jaw member and a movable jaw member cooperating with said fixed jaw member for gripping work, a frame, a foot pedal pivotally mounted on said frame for upward and downward movement, means operatively connecting said foot pedal to said movable jaw member for step by step movement of said movable jaw member toward said fixed jaw member upon actuation of said foot pedal, means for locking said movable jaw member in a selected adjusted position relative to said fixed jaw member, and means for urging said jaw members into spaced relation upon release of said locking means, said connecting means including a feed screw carried by said movable jaw member, a traveling nut block mounted on said feed screw for actuating

the latter, and means connected to said traveling nut block and said foot pedal.

2. The combination of claim 1 wherein said last mentioned means includes a length of chain fixed at one end to said traveling nut block, a further length of chain connected to said foot pedal, and spring means connecting the free ends of said lengths of chain to maintain a constant pressure on the movable jaw member.

BEN E. THOMAS.
